CHANGEABLE EXHIBITOR

Leonard J. Solomon, Forest Hills, N. Y.

Application April 11, 1950, Serial No. 155,235

4 Claims. (Cl. 40—64)

1

My invention relates to changeable exhibitors, and more particularly to exhibitors having a plurality of associated displays, each display changeable independently of the other.

Heretofore whenever it was desirable to associate with a display sheet descriptive indicia, such as a price of the article shown on such sheet, the indicia was usually printed on the sheet. A change in the indicia or the display sheet required an entirely new display which resulted in an expensive process of reprinting and duplication.

It is therefore a primary object of my invention to provide an exhibitor, such as a sign with a plurality of related displays, each display being changeable independently of the other, thus achieving a sign wherein the displays can be reused.

It is a further object of my invention to provide a sign wherein changeable descriptive indicia, such as price, are visible through the main display sheet and is thus closely related to the subject matter displayed.

It is another object of my invention to provide a changeable sign that will accommodate a plurality of displays for storage and display.

Further objects of my invention are to provide a sign of a minimum thickness that can be conveniently used as a counter display or the like and of a construction suitable for mailing; to provide in a sign a compact storage for a plurality of indicia strips which are rapidly accessible and removable for display; to provide a protective transparent covering for said display unit which may be used to conveniently display and store a plurality of display sheets for future use and to provide a sign of a simple construction and adapted to be inexpensively manufactured.

I accomplish these and other objects and obtain my new results as will be apparent from the device described in the following specification, particularly pointed out in the claims, and illustrated in the accompanying drawing, in which—

Fig. 1 is a front elevation view of my novel sign.

Fig. 2 a rear elevation of the same.

Fig. 3 an enlarged side elevation taken along line 3—3 of Fig. 2.

Fig. 4 an exploded front perspective view of the component parts of the sign.

Fig. 5 a front perspective view of the card on which the individual indicia strips are stored, with a portion broken away to show its structure, and

2

Fig. 6 a partial front elevation of a display sheet.

Referring to the drawing, the exhibitor or sign is generally designated as 10, and comprises a transparent cover 11, a front panel 12, intermediate spacer panel 13, and a rear panel 14. The component parts 11 to 14 inclusive may be of substantially the same height and width and are fixedly secured together one adjacent another, preferably by an adhesive, to form an integral frame unit.

The transparent cover 11 may be made of any suitable transparent material, and in its preferred form is constructed of a thin flexible sheet, such as Celluloid. The cover 11 may be formed with bent-over flanges 15, 16 and 17 along the bottom and side edges, respectively, to space the cover from the front panel 12 and form a pocket 18 to slidably receive a main display sheet 19. The top 20 of the cover 11 may be provided with a finger recess 21 to facilitate removal of the display sheet 19 from the pocket 18. The display sheet 19 is provided with a relatively small opening 22, as shown in Fig. 6, forming a window for a purpose later to be described. A backing sheet 23 may be positioned in the pocket 18 to the rear of the display sheet 19 to facilitate mounting the cover 11 to the front panel 12, and may function as a finishing cover sheet for the front panel 12. The backing sheet 23 is likewise provided with a corresponding window 24. The pocket 18 may be of a depth sufficient to accommodate a plurality of display sheets 19, each having a corresponding window 22, so that the display sheets not in use may be conveniently stored one adjacent another within the pocket with their respective windows aligned.

The front panel 12 is constructed of any suitable material, such as cardboard, and is preferably of a thickness sufficient to form a rigid support for the component parts of the unit. The edges of front panel 12 may be bevelled at 25 to enhance the appearance of the sign. A window 26 is provided in the front panel 12 and corresponds with windows 22 and 24.

The intermediate spacer panel 13 is provided with cut-out portions or recesses 27 and 28, with remaining spaced legs 29, 30 and 31, and connecting side portion 32. The recesses 27 and 28 are substantially rectangular and extend from one side 33 of the panel to the connecting side portion 32, forming mouths 34 and 35. The recesses in combination with the legs 29 to 31 inclusive and the front and rear panels 12 and 14, respectively, form pockets 36 and 37, as shown in,

Fig. 3, and the mouths 34 and 35 form entrances for their respective pockets. The pocket 36 is substantially large in height and width to accommodate and store an indicia strip holding card 38, shown in Fig. 5, which has removably mounted thereto a plurality of indicia strips 39. The pocket 37 is positioned to the rear of the window 26 and is of a height and length to receive a plurality of indicia strips 39 adapted to be visible through the windows 22, 24 and 26 as shown in Fig. 1. The inner longitudinal edges of legs 29 and 31 in conjunction with the edges of leg 30, form guideways in the recesses 27 and 28, respectively, to slidably receive the corresponding edges of the card 38 and strips 39. The recess 28 extends sufficiently above and below the window 26 to permit the marginal portion 40 and 41 of the front panel 12 to act as retaining flanges for the indicia strips 39 when inserted into pocket 37.

The rear panel 14 is provided with slots 42 and 43 extending from one edge 44 of the panel, which slots are positioned adjacent pockets 36 and 37, respectively, and are of sufficient height to permit the entrance of a finger into the pockets to assist in the removal of card 38 and indicia strips 39 that are positioned within their respective pockets. An easel 45 is mounted to the rear surface of rear panel 14 to provide a convenient means to support the display on a counter or the like. The easel 45 is preferably constructed of an integral flat sheet of cardboard having an attaching flap 46, which may be glued or otherwise attached to the rear of panel 14; and a leg portion 47 which may be folded normal to the panel 14 into a supporting position and retained by integrally formed locking tab 48. When it is desired to suspend the sign from a wall or the like, a conventional supporting means may be provided.

The indicia strip holding card 38, as illustrated in Fig. 5, is preferably formed of front and rear cardboard sheets 48 and 49, respectively, adhesively or otherwise secured together, and have a combined thickness approximately that of the intermediate panel 13 to permit the card to be slidably received in pocket 36. A plurality of the indicia strips 39 are formed by cutting through the top sheet 48 providing weakened lines 50 to 59 inclusive, which lines define the contour of each indicia strip 39. The areas 54 of the rear sheet 49 adjacent the indicia strips 39 are left free of the adhesive to permit the indicia strips 39 to be ejected from their respective pockets 55 in the card by finger pressure on the rear of sheet 49. The indicia strips 39 fit snugly into their respective pockets 55 in the front sheet 37 so that after use they may be conveniently pressed back therein for storage. As shown in Figs. 1 and 4 the length of the pocket 37 is sufficient to accommodate three indicia strips 56, 57 and 58 to be visible through windows 22, 24 and 26 respectively.

The relative dimensions of the pockets 36 and 37, windows 22, 24 and 26, the card 38, and arrangement and size of indicia strips 39 may vary according to the particular requirements and use of the sign.

The operation of the sign is quite simple. The desired display sheet, such as 19 is inserted into the pocket 18 in the transparent cover 11 so that the window 22 is substantially aligned with windows 24 and 26. The indicia holding card 38 is withdrawn from its pocket 36 and the indicia strips 39 are removed therefrom to make up the desired arrangement and are then inserted in the

pocket 37 in the desired sequence to be visible through the windows 22, 24 and 26, as illustrated by the indicia strips 56, 57 and 58 in Fig. 1. Thereafter the display sheets 19 and the indicia strips 39 can be readily rearranged to meet the instant requirements of the sign.

My invention provides a sign that accommodates a plurality of changeable main display sheets, and a plurality of changeable indicia strips to be visible therethrough. While I have illustrated a numerical designation of the indicia strips, it is to be understood that the type of indicia may be varied as dictated by the needs of the sign. The number and arrangement of indicia strips illustrated on the card may accordingly be changed. By providing a convenient storage pocket for the card in the sign, the indicia strips are readily available with little likelihood of being misplaced. In arranging the indicia strips to be displayed through a window in the display sheets, the window can be changed in location within the display sheet and varied in size to give the desired effect.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished; as it is obvious that the particular embodiments herein shown and described are only some of the many that can be employed to attain these objects and accomplish these results.

I claim:

- 40 1. A display unit comprising a front panel adapted to support a display, said front panel having an aperture therein forming a window, a rear panel and an intermediate spacer panel, means to secure said panels together one adjacent another, said spacer panel having a plurality of recesses, one of said recesses being substantially aligned with said window and forming a pocket between the front and rear panels, whereby an indicia strip may be removably supported in the pocket and visible through said window, another of said recesses forming a pocket between the front and rear panels whereby said indicia strips may be stored when not used for display.
- 45 2. A display unit comprising a panel adapted to support a display, said front panel having an aperture therein forming a window, a rear panel and an intermediate spacer panel, means to secure said panels together one adjacent another, said spacer panel having a plurality of recesses, one of said recesses being substantially aligned with said window and forming a pocket between the front and rear panels, whereby an indicia strip may be removably supported in the pocket and visible through said window, another of said recesses forming a pocket between the front and rear panels whereby a plurality of said indicia strips may be stored when not used for display, said rear section provided with slot portions adjacent said recesses to provide access by a finger into the recesses for removal of the indicia strips.
- 50 3. A display unit comprising a front panel adapted to support a display sheet, said front panel having an aperture therein forming a win-

dow, a rear panel, and an intermediate spacer panel, means to secure said panels together one adjacent another, said spacer panel having a plurality of recesses extending from one end of the spacer panel forming pockets between said front and rear panels, sides of the spacer panel adjacent said recesses forming guideways, an indicia holding card having secured thereon a plurality of removable indicia strips and slidably mounted within one of said recesses, the other recess being substantially aligned with the window and adapted to slidably receive the indicia strips to be visible through said window.

4. A display unit comprising a front panel, a rear panel and an intermediate spacer panel, means to secure said panels together one adjacent the other, a transparent cover mounted to the front panel and spaced therefrom to form a pocket to receive a display, a recess in said spacer

5 panel, an indicia holding card having secured thereon a plurality of detachable indicia strips positioned within said recess, and means to mount said detachable indicia strips adjacent said front panel to be visible through said cover and be associated with said display.
